UNITED STATES PATENT OFFICE.

HIRAM T. BUSH, OF DETROIT, MICHIGAN.

DESIGN FOR A HINGE.

SPECIFICATION forming part of Design No. 34,079, dated February 12, 1901.

Application filed January 15, 1901. Serial No. 43,422. Term of patent 7 years.

To all whom it may concern:

Be it known that I, HIRAM T. BUSH, a citizen of the United States, residing at Detroit, in the county of Wayne and State of Michigan, have invented and produced a certain new and original Design for a Hinge, of which the following is a specification, reference being had therein to the accompanying drawings, in which—

10 Figure 1 is a perspective view, and Fig. 2 is a front elevation.

A and B are two oblong rectangular plates arranged side by side, (in front elevation,) with parallel edges and spaced from each 15 other. C and D are two spherical knobs having a common axis lying in a central plane between said plates.

E and F are necks respectively connecting the knobs C and D with the plates A and B.

G is a rounded bead arranged between and 20 merging into the two spherical knobs.

The leading feature of the design consists in the arrangement of the two plates having parallel edges spaced from each other, the two spherical knobs arranged on a common 25 axis lying in a plane between said plates and the bead between the two spherical knobs.

What I claim as my invention is—

The design for a hinge substantially as 30 herein shown and described.

In testimony whereof I affix my signature in presence of two witnesses.

HIRAM T. BUSH.
